UNITED STATES PATENT OFFICE.

ALBERT BROD, OF NEW YORK, N. Y.

DESIGN FOR A RING.

Application filed October 7, 1924. Serial No. 10,986. Term of patent $3\frac{1}{2}$ years.

To all whom it may concern:

Be it known that I, ALBERT BROD, a citizen of the United States of America, residing at New York, in the county of New York and State of New York, have invented a new, original, and ornamental Design for a Ring, of which the following is a specification, reference being had to the accompanying drawing, forming part thereof.

Figure 1 is a side elevational view, and Figure 2 is an edge view of a ring, showing my new design.

I claim:

The ornamental design for a ring, as shown.

In testimony whereof I affix my signature.

ALBERT BROD.
